(57) **CLAIM**

I claim the ornamental design for an animal-shaped nasal spray dispenser, as shown and described.

DESCRIPTION

FIG. 1 is a top plan view of an animal-shaped nasal spray dispenser according to the present design;
FIG. 2 is a bottom plan view thereof;
FIG. 3 is the front elevation view thereof;
FIG. 4 is the rear elevation view thereof;
FIG. 5 is a front perspective view thereof;
FIG. 6 is a rear perspective view thereof;
FIG. 7 is a right side elevation view thereof;
FIG. 8 is a left side elevation view thereof;
FIG. 9 is an exploded front elevation view of the animal-shaped nasal spray dispenser with the cap unscrewed and the pumping portion of the dispenser separated from the bottle;
FIG. 10 is a rear elevation view thereof;
FIG. 11 is a front perspective view thereof;
FIG. 12 is a rear perspective view thereof;
FIG. 13 is a right side elevation view thereof; and,
FIG. 14 is a left side elevation view thereof.
